UNITED STATES PATENT OFFICE.

ALBERT D. GROVER, OF NEW YORK, N. Y., ASSIGNOR TO AUTOSALES CORPORATION,
A CORPORATION OF NEW YORK.

SLOT-CLOSING DEVICE FOR COIN-CONTROLLED VENDING-MACHINES.

1,391,732.

Specification of Letters Patent. Patented Sept. 27, 1921.

Application filed November 20, 1918, Serial No. 263,252. Renewed February 16, 1921. Serial No. 445,491.

To all whom it may concern:

Be it known that I, ALBERT D. GROVER, a citizen of the United States, and a resident of New York, in the county of New York and State of New York, have invented new and Improved Slot-Closing Devices for Coin-Controlled Vending-Machines, of which the following is a specification.

My invention relates to coin-controlled vending machines, and its object is to provide means for closing or obstructing the coin-entrance slot from the outside of the machine whenever desired, such means being readily removable from the slot by proper manipulation. My invention is particularly applicable in connection with that style of vending machine in which the package of goods is contained in a compartment closed at the top by a lid. These machines, which are of small dimensions and are usually operated in theaters, have one or two compartments, each of which is closed by a lid normally in locked position. When a proper coin is inserted into the coin-entrance slot and the member on the outside operated in the proper direction, the lid is unlocked and flies open, thereby exposing the package of goods for removal by the purchaser. A machine of that general type is shown in Kelly & Webster Patent No. 1,076,769, dated October 28, 1913. As will be understood from the disclosure of that patent, when one or both of the lids are closed and locked, the corresponding coin-entrance slot or slots are open to receive the proper coin. But when one or both of the lids are open, thus indicating that the goods have been sold, the corresponding coin-entrance slot or slots are closed against the further deposit of coins. Whenever the open lids are pressed back into closed position and locked, the coin-entrance slots become automatically clear for the insertion of coins. But, there are times when it is desirable to have the lids locked in closed position and yet have the coin-slots closed against the insertion of coins. This occurs when the compartments are kept empty for one reason or another. To leave the lids open under these circumstances would be highly objectionable, because these lids not only form obstructions on which the clothing of persons passing by may be easily caught and torn, but they render the open machines unsightly and tempt mischievously

inclined persons to fill the open empty compartments with paper and other undesirable matter.

Now, it is the object of the present invention to provide means whereby the coin-slots of these vending machines may be closed against the insertion of coins when the lids are closed. For the sake of illustrating the objects and advantages of my invention, I have shown it applied to a vending machine of the type represented by the theater machine of the Kelly & Webster patent above referred to. In the accompanying drawings—

Figure 1 is a plan view of a two-compartment vending machine provided with a lid for each compartment, one lid being shown open and the other closed;

Fig. 2 is a section on line 2—2 of Fig. 1 looking in the direction of the arrows, and showing the slot-closing device of my invention in position within the coin-passage of the machine;

Fig. 3 is a view similar to Fig. 2, showing how the slot-closing device may be removed through the coin-entrance slot from the outside of the machine;

Fig. 4 is a section approximately on line 4—4 of Fig. 1 looking in the direction of the arrows, showing how the coin-entrance slot of the closed lid is open, while the coin-entrance slot of the open lid is closed by a member of the coin-controlled mechanism in the machine; and

Fig. 5 is a perspective view of the preferred form of my new slot-closing device.

The outer casing A of the machine may be of any approved construction, and in the specific instance is provided with two chambers or compartments B and C, each of which is adapted to contain a package of goods, such as candy and the like. The compartments B and C are closed by the lids B' and C', respectively. These lids are hinged on the rod a at the back of the casing and may be of any approved construction. As shown in the drawings, these lids are on the underside provided with a ledge 1 suitably spaced from the body of the lid. The ledge 1 is provided with a notch or slot 105 2. The lids B' and C' are normally locked in closed position by a pair of slides 3 and 4 having each a rearwardly extending lug 5. The slides 3 and 4 are mounted on a suitable plate 6 by means of studs 7 which 110

engage the slots 8 of the slides. The plate 6 is provided with a slot 9 through which the lugs 5' of the slides 3 and 4 project forwardly into alignment with the coin-entrance slots of the machine. In Fig. 4 the slide 3 is shown in normal or lid-locking position, while the slide 4 is shown in actuated or lid-releasing position. The slide 3 of Fig. 4 corresponds to the closed lid C' in Fig. 1, while the slide 4 corresponds to the open lid B' in Fig. 1. When the slide 3 or 4 is in normal position, the locking lug 5 engages the ledge 1 of the associated lid at one side of the recess 2, as shown at the right of Fig. 1. When the slide 3 or 4 is actuated by the lever 10 into releasing position, the lug 5 is moved into alignment with the slot 2, and the lid flies open under the spring-pressed package in the compartment.

I have not deemed it necessary to illustrate the spring support of the package, because that feature has nothing to do with my invention and is, moreover, an old contrivance, as shown for instance in the patent to Webster No. 1,080,873 issued December 9, 1913.

The lever 10 is pivoted on the plate 6 by means of the stud 11, and is so arranged that its upper end operates between the two slides 3 and 4, moving either of those slides from normal or locking position into lid-releasing position. The lever 10 is at its lower end formed with a rearward extension 12 which projects through the arc-shaped slot 13 of the plate 6 into the path of movement of the coin on the coin-carrier 14. This coin-carrier is in the shape of a disk having a pair of oppositely arranged coin-receiving recesses 15 and mounted to operate in the coin-passage represented as a whole by P. This coin-passage is formed by a recess in the plate or casting S secured at the front of the machine. The coin-carrier 14 is rotatably mounted on this casting by means of a stud 16, and is operatively connected with a hand-wheel or knob 17 on the outside of the casing. The irregularly shaped coin-passage P branches out at the top and forms the two coin-entrance slots p' and p'', through which the coins are inserted into the machine.

Since the coin-controlled mechanism herein illustrated has nothing to do with my present invention, I have not deemed it necessary to illustrate and describe in detail the action of the coin in engaging the extension 12 of the lever 10, because that feature is clearly set forth in the Kelly & Webster patent No. 1,076,769, previously referred to.

The casting S also carries a pair of slideable side latches 18 and 19 which are normally held in uppermost position by the springs 20. Each of the side latches 18 and 19 is provided with a cam extension 21 arranged in the path of the coin on the coin-

carrier 14. When the coin-carrier is rotated with a proper coin, the latter strikes the cam projection 21 and depresses the slide 18 or 19, thereby permitting further rotation of the coin-carrier until the edge of the coin strikes the extension 12 of the actuating lever 10. When this occurs, the upper end of the lever 10 moves against one or the other of the slides 3 and 4 and pushes the same into lid-releasing position. It will be seen from Figs. 1 and 4 that when the slide 3 or 4 is in lid-closing position, the lug 5' rests in the groove or channel 22 of the casting S and is thus out of slot-closing position. In other words, as long as the lid B' or C' is closed, the lug 5' of the associated slide 3 or 4 is out of operative position and the coin-entrance slot is clear for the insertion of a coin. But, when the slide 3 or 4 is actuated into lid-releasing position, the lug 5' extends into the associated coin-passage and thereby closes the coin-entrance slot against the insertion of a coin. This slot-closing position of the lug 5' is shown at the left of Fig. 1 and at the right of Fig. 4.

The function of the spring pressed latches 18 and 19 is to lock the slides 3 and 4 against movement by the lever 10 when the latches are in normal or uppermost position. As this feature forms no part of my invention I have not considered it necessary to illustrate or describe the same in detail, particularly as it is fully set forth in the Kelly & Webster Patent No. 1,076,769, to which reference has been previously made.

It will be clear from the foregoing that as long as the lids B and C are closed, the coin-slots are open for the insertion of coins. On the other hand, as long as one or both of the lids are open, one or both of the coin-slots are closed against the insertion of coins. It should here be stated that the slides 3 and 4 are not spring-actuated, but are passive—that is to say, they remain in actuated position until reset into normal or lid-locking position by a special key from the outside of the casing. So that, when a compartment is empty, the lid remains thrown back in open position until an authorized attendant inserts a key and pushes the slide 3 or 4 back into locking position while holding the lid pressed down. The resetting key engages the lateral projection 23 of the slide 3 or 4. There is an opening (not shown) in each side of the casting S in alignment with the resetting lug 23 in each slide. The lids B' and C' are held in open position by suitable spring mechanism which I do not deem it necessary to show or describe, and I mention it here merely to show why the lids remain thrown back in open position until reset by the attendant. Now, circumstances may arise in which it is desirable or necessary to leave certain machines empty for a period

of time. For instance, there may be a temporary shortage in the supply of the confections sold in the machines, so that it is impossible to replenish the machines. Or, it 5 may be desirable to remove the goods temporarily from the machines, as during the hot months during which the confections melt or otherwise deteriorate in the machines. Or, again, a theater may be closed 10 for a limited period. In these instances, it does not pay to remove the empty machines temporarily from the theater chairs. To leave the machines empty with the lids thrown back, has been found to be objectionable for several reasons. In the first 15 place the machines are unsightly, and the theater managers object to them on that account. The owners of the machines have found that when machines are left empty 20 with the lids thrown back, people fill up the open, empty compartments with paper and other material, which it is exceedingly difficult to remove when the machines are again placed in operation. Then again, lids 25 that are left thrown back form an obstruction on which the clothing of people passing by is caught and torn.

It would not do, when the compartments are empty, to reset the machine and hold 30 the lids closed, for when the machines are thus reset, the coin-entrance slots are open and people would insert coins in the hope of getting goods in exchange.

To overcome the foregoing difficulties, I 35 have devised a new slot-closing device which is readily inserted into the coin-entrance slot when the lids are closed, thereby effectively closing the slot against the insertion of coins. This device is wholly within the 40 coin-passage of the machine and is locked against removal by anyone who does not understand the particular way of manipulating it into unlocked position. In its simplest and preferred form, this slot-closing device is of metal and substantially rectangular in form, one edge being beveled. Where there is a magnet in the machine, such as is used for arresting magnetic slugs, 45 my new slot closing device is preferably of magnetic material, so that the magnet may hold it firmly in locking position within the casing. Referring to the specific embodiment of my invention, as illustrated in the drawings, the slot-closing device is 50 shown in the form of a rectangular piece of metal K, one edge of which is preferably beveled, as indicated at 24. When the member K is inserted into one of the coin-entrance slots (as in the slot p' in Fig. 2), it 55 assumes, or is readily manipulated to assume, the position shown in Fig. 2. It will be seen from that figure, that the member K lies entirely within the coin-passage and is thus practically hidden from view. In 60 inserting the member K into the machine, the beveled edge 24 should be on top. This renders the member K more difficult to be seen and more difficult to remove. As will be clear from Fig. 2, when properly inserted, the slot-closing device K is locked 70 within the machine, due to the fact that one edge of the member engages the projection 25. When it is attempted to turn the coin-carrier in the direction indicated by the arrow α in Fig. 2, the point 14^a of the 75 coin-carrier strikes the member K beyond the center thereof and so forces the same against the projection 25 and against the point 26 of the casting S. The point 26 forms part of the wall of the coin-passage 80 which is formed in the casting S. When the coin-carrier is turned in the opposite direction, the point 14^b of the coin-carrier forces the member K against the point 26 of the casting. Thus, it will be seen that the member K is effectively locked within the coin-passage of the machine and also locks the coin-carrier against rotation, except for a limited amount of movement. It will further be apparent from Fig. 2 that only one 85 slot-closing member is necessary to close both coin-slots of the machine. For, while the member K closes the coin-slot in which it is inserted, the coin-carrier 14 is in such a position that it closes the other slot against 90 the insertion of coins. This is clear from Fig. 2, where the dotted circle N indicates the position of a coin attempted to be inserted. The coin N rests on the circular periphery 14^c of the coin-carrier and may 95 be withdrawn by hand.

The removal of the slot closing member K is a very simple matter when a person knows how to do it. All that is necessary is to insert a tool into the closed coin-slot 100 and press it gently down on the upper edge 24 of the member K at a point approximately as indicated in Fig. 3, where the inserted tool is represented by the dotted lines T. This downward pressure on the 105 member K causes the same to be tilted in such a way that the corner k thereof is moved out of engagement with the locking projection 25. It will be understood that when this rocking or turning of the member K takes place, the coin-carrier 14 has been manipulated from the exact position shown in Fig. 2 to a position in which the point 14^a is slightly below the lower edge 110 of the member K, so as to give the latter a 115 chance to rock out of locking position. As soon as the member K is manipulated into unlocking position, the coin-carrier 14 is turned in the direction indicated by the arrow α in Fig. 3, which causes the point 14^a 120 of the coin-carrier to push the member K out of the coin-slot p'. The projecting portion of the member K may then be grasped 125 by the fingers and the member moved.

Where the machine in which my slot- 130

closing device is used contains a magnet which is employed for coin-testing purposes, it is desirable that the member K be of magnetic material. In the machine 5 shown by way of illustration in the accompanying drawings, there is a magnet M mounted on the casting S in such position that the poles thereof extend in close proximity to the coin-passage, whereby magnetic slugs are attracted to the magnet. It will not be necessary to describe here in detail the coin-testing function of the magnet M, since that forms no part of my present invention and since, furthermore, the 10 magnetic coin-testing mechanism of which the magnet M is a part is fully disclosed in Grover & Barber Patent No. 1,180,713, dated April 25, 1916. It is sufficient to say here that when the member K is of magnetic 15 material and is inserted into either one of the coin-slots p' or q', the poles of the magnet M hold the member K in stationary position. This prevents rattling of the member K when the coin-carrier 14 is oscillated. 20 Such rattling would be objectionable in a theater, and would moreover let the public know that there was something loose in the coin-slot. The result of this would be that many persons would try to get that rattling 25 piece of metal out of the machine. But, with the member K held stationary by the magnet M, a person attempting to rotate the knob 17 on the outside of the machine would 30 simply find that the machine was locked, 35 without being given any indication of how it was locked.

It will be seen from the foregoing that I have provided a very simple and effective means for locking the slots when the lids 40 of the machines are closed. All that the attendant has to do in order to lock the slots when the lids are closed is to insert a member K in either one of the slots of each machine. When it again becomes necessary or 45 desirable to put the machines in operative condition, the attendant need only remove the inserted members K to clear the coin-slots. By a skilled person this may be done very quickly.

50 Although I have shown and described my invention as applied to a vending machine of the lid type, it is obvious that it is not limited to that particular type of machine, although it finds a peculiar usefulness in that connection.

Having thus described my invention, what I claim as new and desire to secure by Letters Patent of the United States, is:

1. In a coin-controlled vending machine, 60 a casing having a compartment for containing the vendible package, a normally closed lid for said compartment, said casing being provided with a coin-entrance slot which is open when the lid is closed, coin-controlled mechanism for opening said lid, said mecha-

nism including means for automatically closing said coin-entrance slot when the lid is open, and a member constructed to be fully inserted into said coin-entrance slot when the lid is closed, whereby said slot is 70 closed against the insertion of a coin, said member being readily adjustable in said slot to cause a portion thereof to project out of the casing for removal through said slot.

2. In a coin-controlled vending machine, 75 a casing having a compartment for containing the vendible package, a normally closed lid for said compartment, a hand-operable coin-carrier, said casing being provided with a coin-entrance slot and with a coin-passage 80 leading from said slot to said coin-carrier, mechanism controlled by the coin in said carrier for opening said lid, said mechanism including means for automatically closing said slot when the lid is open, said means 85 being out of slot-closing position when the lid is closed, a projection in said coin-passage, and a member constructed to be fully inserted through said slot into said coin-passage to close said slot and lock said coin-carrier, said member being adapted to engage said projection and thereby become locked in said passage but being readily moved out of engagement with said projection, whereupon said coin-carrier may be 90 operated to project said member out of said slot for removal.

3. In a coin-controlled vending machine, 95 a casing having two compartments for the vendible packages and a coin-entrance slot 100 for each compartment, a normally closed lid for each compartment, a hand-operable coin-carrier for receiving the deposited coin, there being a coin-passage leading from each slot to said coin-carrier, a projection in each 105 coin-passage, mechanism controlled by the coin in said carrier for unlocking the lid corresponding to the slot through which the coin is inserted, said mechanism including means for automatically closing one or both 110 coin-entrance slots when one or both lids are open, said means being out of slot-closing position for either slot when the corresponding lid is closed, and a member constructed to be inserted fully through either 115 slot into the corresponding coin-passage and to engage the projection in said passage, whereby said member is locked in said passage to close the associated coin-entrance slot and lock the coin-carrier, the other slot 120 being closed against the insertion of a coin by said locked coin-carrier, said member being readily moved out of engagement with said projection, whereupon said coin-carrier may be operated to project said member out 125 of the slot for removal.

4. In a coin-controlled vending machine, 130 a casing having a compartment for containing the vendible package, a normally closed lid for said compartment, a hand-operable

- coin-carrier, said casing being provided with a coin-entrance slot and with a coin-passage leading from said slot to said coin-carrier, mechanism controlled by the coin in 5 said carrier for opening said lid, said mechanism including means for automatically closing said slot when the lid is open, said means being out of slot-closing position when the lid is closed, a projection in said 10 coin-passage, a magnet having its poles in close proximity to said coin-passage, and a magnetic member constructed to be fully inserted through said slot into said coin-passage to close said slot and lock said coin-carrier, said member being adapted to engage said projection when acted upon by 15 the coin-carrier and thus become locked in said passage, said magnet holding the magnetic member firmly in locked position but 20 permitting adjustment of the member out of engagement with said projection, whereupon the coin-carrier may be operated to project the unlocked member out of the coin-entrance slot for removal.
- 25 5. In a coin-controlled vending machine, a casing provided with a coin-entrance slot, a rotatable coin-disk for receiving the de-
- posited coin and carrying the same into operative position, and a substantially rectangular member constructed to be inserted 30 fully into said slot to close said slot and lock said disk against rotation, said member being locked within the casing but being readily adjustable from the outside into unlocked position, whereupon said disk may 35 be operated to project said member through said slot for removal.
6. In a coin-controlled vending machine, a casing provided with a coin-entrance slot, a hand-operable coin-carrier for receiving 40 the deposited coin and carrying the same into operative position, and a member constructed to be inserted fully into said slot to close said slot and lock said coin-carrier against operation, said member being locked 45 within the casing but being readily adjustable from the outside into unlocked position, whereupon said coin-carrier may be operated to project said member through said slot for removal. 50

In witness whereof, I hereunto subscribe my name this 12 day of November, 1918.

ALBERT D. GROVER.
